US00D866665S

(12) **United States Design Patent** (10) **Patent No.:** **US D866,665 S**
(45) **Date of Patent:** **** Nov. 12, 2019**

(54) **GAME BOARD**

(71) Applicants: **Josh J. Palmer**, Willsboro, NY (US);
Kenny Alterie, Peru, NY (US)

(72) Inventors: **Josh J. Palmer**, Willsboro, NY (US);
Kenny Alterie, Peru, NY (US)

(**) Term: **15 Years**

(21) Appl. No.: **29/627,941**

(22) Filed: **Nov. 30, 2017**

(51) LOC (12) Cl. **21-01**

(52) U.S. Cl.

PLLC; Aaron R. Cramer

(57) **CLAIM**

The ornamental design for a game board, as shown and
described.

DESCRIPTION

FIG. 1 is a perspective top front right view of a game board,
showing our new design;
FIG. 2 is a perspective bottom rear left view thereof;
FIG. 3 is a front elevation view thereof;
FIG. 4 is a rear elevation view thereof;
FIG. 5 is a right side elevation view thereof;
FIG. 6 is a left side elevation view thereof;
FIG. 7 is a top plan view thereof; and,
FIG. 8 is a bottom plan view thereof.
